UNITED STATES PATENT OFFICE

2,558,325

MULTIOILSTONE

Walter Dorwin Teague, Annandale, N. J., and Gordon M. Peltz, Kew Gardens, and Carl W. Hubbinette, Troy, N. Y., assignors to Behr-Manning Corporation, Troy, N. Y., a corporation of Massachusetts

Application May 5, 1949, Serial No. 91,558

15 Claims. (Cl. 51—213)

1

The present invention relates to an oilstone sharpening apparatus and constitutes a modification of and an improvement upon devices of the kind shown in the prior Patent No. 1,946,968, F. E. Gallagher, February 13, 1934. Reference is made to that patent for an explanation of the objects, advantages, and field of usefulness of such devices.

The primary object of the present invention is to simplify the construction and to reduce the cost of manufacture of oilstone sharpening devices, as compared with the construction shown in the above mentioned patent, without sacrificing any of the advantageous features thereof.

A further object of the invention is to provide improved and simplified means for preventing movement, longitudinally, transversely and rotationally, of the oilstone holder, relative to the base containing the oil reservoir.

A further object of the invention is to provide an improved form of base, particularly adapted to be cast or molded from plastic material, such as synthetic resin molding compositions.

Another object is to provide an oilstone sharpening apparatus, in which the oilstone holder may be rotated from one position to another, to bring one of a plurality of oilstones to the working position, in a most expeditious manner and in which the holder may be quickly and simply locked in position, against inadvertent relative movement with respect to the base.

Another object is to provide a construction which permits the above mentioned manipulation by the use of only one hand of the operator.

Other and further objects and advantages of the invention will be apparent from a consideration of the following description of the embodiments described below and shown for purposes of illustration in the accompanying drawings, in which

Figure 1 is a plan view of the base and holder, and a fragmentary portion of the cover;

Figure 2 is a longitudinal section on line 2—2 of Figure 1;

Figure 3 is a transverse section on line 3—3 of Figure 1;

Figure 4 is a similar section on line 4—4 of Figure 1;

Figure 5 is a section on line 5—5 of Figure 1;

Figure 6 is a sectional view of the holder on line 6—6 of Figure 2;

Figure 7 is a fragmentary section and elevation of a modified form of the invention;

Figure 8 is an end elevation, taken substantially on line 8—8 of Figure 7, showing one ele-

ment of a locking connection between the base and holder;

Figure 9 is a similar view, taken substantially on line 9—9 of Figure 7, showing the other element;

Figure 10 is a view similar to Figure 4, of a third modification;

Figure 11 is an end view of the stone supporting block in accordance with this modification, and

Figure 12 is a vertical section and side elevation, showing the cooperative relation of the locking members shown in Figures 10 and 11.

The base 10 is preferably formed of molded or cast plastic material and comprises exterior, downwardly extending side walls 11 and 12 and similar end walls 13 and 14, the latter being extended upwardly to the plane 15, above the upper edge 16 of the side walls. The upwardly extending end walls 13 and 14 are bifurcated or provided with upwardly opening, central slots 17 and 18, for the reception of the shaft of the oilstone holder, as hereinafter explained.

The side and end walls of the base are integral with interior reservoir-defining walls, including curved side and bottom surfaces 20 and inwardly and downwardly sloping end walls 21 and 22. Secured to the inclined end face 21, by countersunk screws 23 or the like, is a U-shaped cam or wedge element 24, having its legs extending upwardly in straddling relation to the slot 17.

The other end face 22 of the reservoir has formed thereon a pair of inwardly projecting bosses 25 and 26, upon the upper surface of which there is secured, by screws 27 or the like, an upwardly extending, locking member 28, having an upwardly opening central slot 29 therein. Each of the upwardly extending legs 30 and 31 of the member 28 has a downwardly and outwardly inclined, overhanging or undercut abutment surface 32, 33, for purposes hereinafter explained.

The oilstone holder comprises a central shaft 35, upon which a plurality of stone carrying blocks 36, 37, and 38 are mounted, by means of appropriate set screws, dowel pins or the like. The end blocks 36 and 37 may be substantially identical, to reduce the cost of production, but they are assembled on the shaft, differently, to cooperate in different manners with the adjacent end surfaces of the base. Each of these blocks is of generally triangular form in elevation, except that the apices or corners are cut away, providing three elongated plane edge faces 39, 40, and 41, and three relatively short plane edge faces 42, 43, and 44. One vertical end

face of each block is plane as indicated at 45, while the other projects longitudinally and has a three-legged spherical surface 46, connected to the main body of the block by inclined plane faces 47, 48, and 49.

The central block 38 constitutes a similarly shaped, thinner member, but both of its end vertical faces may be planar, as indicated at 50 and 51.

Three oilstones 55, 56, and 57, of varying degrees of coarseness may be secured to the edge faces of the blocks 36, 37, and 38 by clamping strips 58, 59, and 60, by means of screws 61 having their heads countersunk therein and their shanks extending into tapped bores 62 in the small edge faces 42, 43, and 44 and in the corresponding faces of the center block. Spacer collars 63 may be interposed between the strips and the blocks, to prevent the strips from being drawn inwardly so tightly as to damage the edges of the oilstones.

Handles 65 and 66 may be secured to the ends of the shaft 35 by set screws or the like. Preferably, the handles are triangular in shape, to correspond to the triangular assembly of the stones on the holder.

A cover 67 has the lower edge of its down-turned ends 71 and 72 and sides 73 and 74 supported in a rabbet 75, extending continuously around the inner surfaces of the side and end walls adjacent the upper edges thereof.

In the use of this form of the invention, when the parts are in the position shown in Figure 2, the holder is locked against inadvertent movement relative to the base. The cam following surface 46 of the end block 36 is resting upon the cam plate 24, with the result that the holder as a whole is urged toward the opposite end of the base, by a wedging or camming action, due to the inclination of the plate and the influence of gravity. The other end block 37 has its upper edge or corner disposed in contact with the inclined, undercut or overhanging abutment surfaces 32 and 33 of the locking member 28. Hence, rotation of the holder as a whole is prevented. Similarly, longitudinal and transverse movement of the holder is prevented by the wedging action and by reason of the fact that the spherical surface 46 tends to center itself in the U-shaped cam plate 24.

When it is desired to bring another stone to the uppermost position, the operator simply lifts the right-hand handle 65, moves the holder as a whole slightly to the right, to free the block 37 from the abutment surfaces 32 and 33, and rotates the holder. The shaft 35 turns readily in the bottom of the slot 29 of the locking member 28. Hence, it is unnecessary to lift both ends of the holder. After the desired stone has been raised, the right-hand handle is lowered, whereupon the holder is automatically urged toward the left, the stone is brought to accurately aligned horizontal position by the engagement of the abutment surfaces 32 and 33 with the now uppermost edge or corner of the block 37 and the parts are locked.

Of course, the reservoir is kept substantially filled with oil, so that the stones are flushed of abraded matter and are supplied with lubricant by immersing them in the oil, as explained in the above identified patent.

In the modification shown in Figures 7, 8, and 9, a different form of locking interconnection is employed, but otherwise the apparatus may be the same. The member 28a, instead of having

an overhanging surface, as previously described, carries a forwardly projecting rib 80, having tapering side faces 82 and 83. The end block 37a, mounted on the central shaft 35a may be substantially identical to the block 37, except that in its outer, vertical end face, it is provided with three radially extending slots 84, 85, and 86, each of which is adapted to receive and embrace the rib 80, when in the downwardly extending position, as indicated in Figure 7. The inclined side faces of the rib wedge themselves against the corners of the groove, as the holder is urged toward the left, as previously explained, by a cam at the right-hand end.

In the form of the invention shown in Figures 10, 11, and 12, the inwardly projecting bosses 25b and 26b support a locking member 28b having a pair of upwardly extending legs 90 and 91, shaped at their upper ends to provide laterally and inwardly turned abutment hooks 92 and 93. The inside surfaces of the legs and the hooked ends define a socket 94, which may taper somewhat toward the adjacent, upstanding end wall 14b of the base. Surfaces 95, 96 converge downwardly and meet at a central line of junction 97. Hence, the socket or recess 94 is generally triangular in shape, with the apex 97 pointing downwardly.

The stone supporting block 37b may be quite similar to, or substantially identical with, the one shown in the first form of the invention, except it is turned around, end for end, with the laterally projecting portion thereof facing the locking member 28b. The latter portion is generally pyramidal in configuration and includes three elongated, substantially plane side faces 98 and three corner faces 99, joining a substantially spherical end face 100, having three laterally extended portions 101, in alignment with the corner faces 99.

In use, the inclined, wedge or cam surface at the opposite end of the base (not shown) urges the projecting end of the stone supporting block 37b into the socket 94 in the locking member 28b, as shown in Figure 12, with one of the corners thereof seated in the bottom 97 of the socket and with the overhanging ends or abutment hooks 92 and 93 engaging the edge of the uppermost side face 98. Hence, rotation of the stone holder is prevented. When the opposite end is lifted, however, and the holder shifted toward the right (Figure 12), the shaft 35b of the holder will be supported by the bottom 14b of the slot in the end wall 14b of the base. Hence, the holder may be rotated in the same manner and for the same purposes as previously described.

The invention is not limited to the details of construction shown in the accompanying drawings of three preferred embodiments of the invention and described above, but includes all modifications coming within the scope of the appended claims and their equivalents.

We claim:

1. A sharpening apparatus comprising a base having an upwardly facing oil reservoir therein, an abrasive stone holder, and a plurality of stones mounted thereon, said base having a downwardly and inwardly inclined interior surface adjacent one end thereof, engageable under the force of gravity by an adjacent end surface of said holder and tending to move the holder longitudinally toward the other end of the base, and connecting means between the other end of the holder and said other end of said base, rendered effective by longitudinal movement of the holder in said direction and preventing relative move-

ment between the two when the holder is so moved.

2. A sharpening apparatus comprising a base having an oil reservoir formed therein, an oil-stone holder, and a plurality of oilstones mounted thereon, said base having a downwardly and inwardly inclined interior surface adjacent one end thereof, engageable under the force of gravity by an adjacent end surface of said holder and tending to move the holder longitudinally toward the other end of the base, and an overhanging abutment at the last mentioned end of the base positioned to be engaged by the other end of the holder when the latter is so moved and preventing relative movement between the two when the holder is so urged.

3. A sharpening apparatus comprising a base having a reservoir formed therein, an oilstone holder and a plurality of oilstones mounted thereon, said base having slotted, upwardly projecting end walls at both of its ends, a downwardly and inwardly inclined interior surface adjacent one end thereof, and a pair of overhanging abutment surfaces disposed on opposite sides of the slot at the other end thereof, said holder comprising a shaft adapted to be received in said slots, means on the shaft for supporting a plurality of oilstones in angular relation parallel to the shaft, a surface at one end of the holder engageable under the force of gravity with said inclined surface to move the holder longitudinally of the base toward the other end thereof, and a surface at the other end engageable with said overhanging abutment surfaces when the holder is so moved and preventing relative movement between the holder and the base.

4. A sharpening apparatus comprising a base having an oil reservoir formed therein, an oil-stone holder, and a plurality of oilstones mounted thereon, said base having a downwardly and inwardly inclined interior surface adjacent one end thereof, engageable under the influence of gravity by an adjacent end surface of said holder and tending to move the latter longitudinally toward the other end of the base, and a rib and groove connection between the other end of the holder and said base preventing relative movement between the two when the holder is so moved.

5. A sharpening apparatus comprising a base having an oil reservoir formed therein, an oil-stone holder, and a plurality of oilstones mounted thereon, said base having a downwardly and inwardly inclined interior surface adjacent one end thereof, engageable under the force of gravity by an adjacent end surface of said holder and tending to move the latter longitudinally toward the other end of the base, a rib projecting inwardly into the reservoir from the other end of the same, and means at the other end of the holder defining a plurality of grooves adapted to embrace said rib to prevent relative movement between the holder in the reservoir when the holder is so moved.

6. A sharpening apparatus comprising a base having an oil reservoir formed therein and having upwardly projecting, centrally slotted end walls, a downwardly and inwardly inclined cam surface at one end and an angular, transverse abutment at the other end, and an oilstone holder having shaft extensions at opposite ends receivable in the slots in the ends of the base, a cam following surface engageable under the force of gravity with said inclined surface to move the holder toward the other end of the base, and a locking surface at the other end of the holder engageable

with said transverse abutment of the base when the holder is so moved to prevent rotation of the holder relative to the base.

7. An oilstone sharpening apparatus comprising a unitary base shaped to provide an upwardly facing oil reservoir and having vertically slotted end walls projecting upwardly beyond the side walls thereof, one of said end walls having a downwardly and inwardly inclined inner surface, a locking member carried by the other end wall having a slot aligned with the slot therein and a transverse abutment surface on the inner face thereof, and an oilstone holder comprising shaft extensions at both ends receivable in the end wall slots, a cam follower carried by one shaft extension engageable under the force of gravity with said inclined surface to move the holder toward the opposite end of the base and a locking member carried by the second shaft extension engageable with the abutment surface on the first mentioned locking member when so moved, the locking members being releasable when the first shaft extension is raised and shifted in the other direction, and the holder being rotatable while the second shaft extension is supported on the bottom of the slot of the first mentioned locking member.

8. An apparatus in accordance with claim 7 in which the first mentioned locking member has a pair of inwardly projecting, overhanging, inclined abutment surfaces and in which the locking member on the holder has a plurality of edge surfaces selectively engageable thereunder.

9. An apparatus in accordance with claim 7 in which the abutment surfaces on the first mentioned locking member are constituted by a projecting rib and in which the cooperating surfaces on the other locking member are constituted by a plurality of grooves extending radially from the shaft extension and selectively engageable with said rib.

10. An apparatus in accordance with claim 7 in which the cam following surface is formed on the end face of an oilstone supporting block and in which the abutment surfaces on the second mentioned locking member are formed on another oilstone supporting block.

11. An oilstone sharpening apparatus comprising a base shaped to provide an upwardly facing oil reservoir and having an upwardly facing slot at one end and a downwardly and inwardly inclined, cam surface adjacent said slot, an upwardly opening slot adjacent the other end and a transverse abutment surface adjacent the last mentioned slot, and an oilstone holder having a shaft extension at one end receivable in the first slot, a cam following surface seated under the force of gravity upon the adjacent inclined surface and forcing the holder toward the other end of the base, a shaft extension at the other end of the holder seated in the bottom of the second slot, and a transverse abutment surface at the last mentioned end of the holder held in engagement with said abutment surface on the base by the force of the cam and cam follower, the last mentioned shaft extension being supported for rotation in the bottom of the second slot when the other shaft extension is lifted and the abutment surfaces are disengaged by endwise movement of the holder.

12. A sharpening apparatus comprising a base having an upwardly facing oil reservoir formed therein, an oilstone holder and a plurality of oilstones mounted thereon, said base having at one end thereof surfaces forming an inwardly facing

non-circular socket, said oilstone holder having at the adjacent end, a noncircular outward projection adapted to enter the socket by endwise movement of the holder and having surfaces engageable with the surfaces of the socket to prevent upward and rotational movement of said end of the holder, and interengaging surfaces at the other end of the holder and the base, permitting lifting movement of the holder at that end, but preventing endwise withdrawal of said projection from said socket when the last mentioned end of the holder is in the lowered position.

13. A sharpening apparatus comprising a base having an upwardly facing oil reservoir formed therein, an oilstone holder having means for securing three oilstones thereon in longitudinally extending, triangularly arranged relation, said base having at one end a plurality of surfaces forming an inwardly facing triangular socket, said oilstone holder having at the adjacent end a triangular outward projection adapted to enter the socket by endwise movement in any one of three different positions in which each of the oilstones is disposed upwardly, selectively, said projection having surfaces engageable with the surfaces of the socket to prevent upward and rotational movement of said end of the holder, the other end of the base having a downwardly inclined interior surface and the other end of the holder having a surface engageable therewith to urge the first mentioned end of the holder longitudinally toward the socket.

14. An oilstone holder comprising a longitudinally extending shaft, a plurality of blocks carried by said shaft in longitudinally spaced relation, each of said blocks having a plurality of transversely elongated, angularly disposed seating surfaces on its edges and additional corner surfaces of less length therebetween, a corre-

sponding number of longitudinally extending oilstones disposed upon said seating surfaces, a plurality of longitudinally elongated clamping strips having their opposite edges in engagement with the longitudinal side edges of adjacent oilstones, and means connecting said strips to said corner surfaces for drawing the strips inwardly to clamp the stones upon the seating surfaces.

15. An oilstone holder comprising a longitudinally extending shaft, a plurality of blocks carried by said shaft in longitudinally spaced relation, each of said blocks having three transversely elongated, triangularly disposed seating surfaces and intermediate, truncated corner surfaces therebetween, three longitudinally extending, angularly arranged oilstones disposed upon said seating surfaces, three longitudinally elongated clamping strips having their opposite edges in engagement with the longitudinal side edges of adjacent oilstones inwardly of the outer faces thereof, and a plurality of screws extending through said strips and connected to said corner surfaces for drawing the strips inwardly to clamp the stones upon the seating surfaces.
